UNITED STATES PATENT OFFICE

120,636

DESIGN FOR A SPORTS JACKET

Benjamin Breier, Amsterdam, N. Y., assignor to Adirondack Sportswear, Inc., Amsterdam, N. Y., a corporation of New York

Application January 9, 1940, Serial No. 89,363

Term of patent 7 years

To all whom it may concern:

Be it known that I, Benjamin Breier, a citizen of the United States, residing at Amsterdam, in the county of Montgomery and State of New York, have invented a new, original, and ornamental Design for a Sports Jacket, of which the following is a specification, reference being had to the accompanying drawing, forming part thereof.

Fig. 1 is a side view of a sports jacket embodying my new design, and

Fig. 2 is a rear view of the jacket illustrating the design of the back and side portion of the garment.

The front of the jacket is conventionally plain.

I claim:

The ornamental design for a sports jacket, as shown and described.

BENJAMIN BREIER.
